UNITED STATES PATENT OFFICE

153,574

DESIGN FOR A TWIN BED UNIT

Truman S. Ziegenfuss, Los Angeles, Calif.

Application September 2, 1947, Serial No. 141,160

Term of patent 14 years

(Cl. D5—2)

To all whom it may concern:

Be it known that I, Truman S. Ziegenfuss, a citizen of the United States, residing at Los Angeles, in the county of Los Angeles and State of California, have invented a new, original, and ornamental Design for a Twin Bed Unit, of which the following is a specification, reference being had to the accompanying drawing, forming part thereof.

Figure 1 is a perspective view of a twin bed unit, showing my new design, and with the beds therein in open position;

Figure 2 is a plan view of the unit shown in Figure 1; and

Figure 3 is a perspective view of the unit shown in Figure 1 but with the beds in closed position.

I claim:

The ornamental design for a twin bed unit, substantially as shown.

TRUMAN S. ZIEGENFUSS.
